(57) **CLAIM**

The ornamental design for a mobile phone, as shown and described.

DESCRIPTION

FIG. 1 is a front perspective view of the mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The dash-dot broken lines define the bounds of the claimed design and form no part thereof, all surfaces within the dash-dot broken lines form part of the claimed design. The dash-dash broken lines, including the four individual broken lines that occur within the bounds of the claim, depict portions of the mobile phone that form no part of the claimed design.
